[57] CLAIM

The ornamental design for device for accumulating, amplifying and directing cosmical energy, as shown and described.

DESCRIPTION

FIG. 1 is a front/bottom perspective view of a first embodiment of a device for accumulating, amplifying and directing cosmical energy showing my new design;

FIG. 2 is a top view thereof;

FIG. 3 is an elevational view thereof, the other elevations being the same, because of rotational symmetry and, therefore, not being shown;

FIG. 4 is a bottom view thereof;

FIG. 5 is a front/bottom perspective view of a second embodiment, the bottom front not being shown because symmetrical with the bottom rear that is shown;

FIG. 6 is a top view of the second embodiment; and,

FIG. 7 is an elevational view of the second embodiment, the other elevations being the same, because of rotational symmetry and, therefore, not being shown.
